UNITED STATES PATENT OFFICE.

FRANCIS F. HAMILTON, OF INDIANAPOLIS, INDIANA.

DESIGN FOR A BOX.

Application filed June 7, 1926. Serial No. 17,965. Term of patent 7 years.

To all whom it may concern:

Be it known that I, FRANCIS F. HAMILTON, a citizen of the United States, residing at Indianapolis, in the county of Marion and State of Indiana, have invented a new, original, and ornamental Design for a Box, of which the following is a specification, reference being had to the accompanying drawing, forming a part thereof, of which the following is a specification.

Referring to the drawing—

Fig. 1 is a front side elevation of a box embodying my design;

Fig. 2, a top plan view of the box; and
Fig. 3, an end elevation of the box.

The box is finished in red cedar and the trimmings are in a contrasting color.

I claim:

The ornamental design for a box, as shown and described.

In testimony whereof I affix my signature.

FRANCIS F. HAMILTON.
